ARTHUR WILLIAM HARRIS, OF NEW YORK, N. Y., ASSIGNOR TO THE AMPLION CORPORATION OF AMERICA, OF NEW YORK, N. Y., A CORPORATION OF DELAWARE.

SOUND-REPRODUCING INSTRUMENT.

Application filed June 23, 1926. Serial No. 118,094.

This invention relates to an instrument for reproducing sound waves of such frequencies as to be appreciated by the human ear. In particular, the invention has to do with a 5 novel construction of a sound reproducing instrument such as is now generally known as a speaker or a loud speaker.

In the development of the loud speakers adapted particularly for use with wireless 10 receiving sets, great difficulties have been met in unsuccessful attempts to construct a single instrument which will reproduce the low notes as well as the high notes. Experience has shown that a speaker which satisfactorily reproduces the low frequency 15 notes does not satisfactorily reproduce the high frequency notes and vice versa.

The present invention has to do with an improved loud speaker instrument which 20 will satisfactorily and with exceeding efficiency reproduce low frequency notes as well as high frequency notes. This improved speaker also has in its favor a considerably wider range of efficient and satisfactory 25 production than has heretofore been accomplished in loud speakers of this type.

The main object of this invention is, therefore, to provide a novel construction of sound wave reproducing mechanism whereby notes 30 of both low and high frequencies will be satisfactorily and clearly reproduced.

Another object of this invention is to provide a novel speaker which has a particularly wide range of note reproduction and 35 which reproduces notes of high frequencies substantially as well as notes of low frequencies and vice versa.

A further and detailed object of this invention is to provide a novel combination 40 of a relatively small vibrating diaphragm with a cone of modified form, in a loud speaker of the cone type whereby a very advantageous improvement with increased range of sound reproduction is obtained.

45 Another object of the invention is to supplement a combined diaphragm and cone speaker with a horn to thereby add to the total efficiency of the improved speaker.

A still further object of the invention is 50 to provide a novel type of loud speaker which is exceptionally simple in its construction and operation and has vibrating elements of desirably light weight, rendering

it more sensitive and permitting its manufacture at a relatively low cost.

Other objects and advantages of the invention will be appreciated as the detailed description below is read.

The preferred embodiment of this invention is illustrated in the accompanying 60 drawings wherein:

Fig. 1 is an elevational view, partly in section, of the improved speaker showing a modified form of cone vibrating member affixed to a diaphragm;

Fig. 2 is an illustration similar to Fig. 1 and includes a showing of a guard for the protection of the cone;

Fig. 3 is also an elevational view based on the construction shown in Fig. 1 and illustrates in addition thereto, the use of a horn which assists in the amplification of the sound waves and also acts to protect the cone;

Fig. 4 is a top plan view of a means for 70 vibrating the diaphragm and cone member;

Fig. 5 is a sectional view of Fig. 4 taken on the line 5—5 thereof;

Fig. 6 is a sectional view of the operating mechanism shown in Fig. 4 taken on the line 6—6 of Fig. 5; and

Fig. 7 is a perspective view of an element employed in the mechanism shown in Fig. 4.

In producing this novel type of simple loud speaker, there is preferably combined two vibrating elements in such a satisfactory manner as to obtain a very efficient reproduction of sound waves over an exceptionally wide range. In carrying out the most preferred method of combining these elements, there is provided a vibrating part which is particularly adapted to the efficient reproduction of notes of high frequencies, and there is also provided a second vibrating part which most efficiently reproduces notes of low frequencies. These parts have been brought into association with one another so that, in their normal operation, they vibrate in unison and effect a very pleasing reproduction of speech and musical notes over a wide range.

In combining these two vibrating parts or elements, there results a sound reproducing mechanism which may appropriately be termed a compound vibrator. It will be understood that the two elements may be

combined in any desired manner to accomplish the desired improved result as herein required to be obtained. It is believed, however, that one of the reasons for obtaining 5 the highly satisfactory results accomplished according to this invention, resides in the fact that one of these vibrating elements is attached to the other vibrating element at some place or portion thereof which normally vibrates during the operation of the speaker. Whether or not this is the explanation or main reason for obtaining such advantageous results, the improved speaker mechanism according to the invention herein 10 in illustrated and described has proven to produce most satisfactory results in operation.

In describing the preferred embodiment of the invention in a particular apparatus, 20 or instrument, reference is made especially to Fig. 1 wherein a suitable base-holder 1 is illustrated as having one of the vibrating elements in the form of a diaphragm 2 mounted therein. This disk diaphragm 2 is preferably of metallic construction and is fixedly or semi-fixedly mounted in the base-holder. It is preferred that this diaphragm 2 shall be annular and shall be either permanently and firmly mounted between a lip 25 30 of the base-holder 1 and a cover edge 4, or between suitable rubber or resilient spring gaskets. Thus, the diaphragm 2 is fixedly mounted in the base-holder in a predetermined manner. It is also to be understood 35 that this diaphragm may be affixed or permanently mounted to the base-holder 1 in any other suitable manner.

To the diaphragm 2 there is added a second vibrating element or diaphragm 5, preferably in the form of a cone, and it is preferred to have this cone of materially greater size than that of diaphragm 2. This cone 5 in addition to constituting a vibrating member, also may function as a horn 40 for amplifying the sound waves which are set up within the confines of the element 5 by the vibrations of that part or portion of the diaphragm 2 confined within or lying adjacent to the smaller edge of the cone. 45 The cone vibrating element or part may be made of any suitable material which is adapted to reproduce sound waves when this material is vibrated. In this instance, it is advantageous to make the cone 5 of a suitable paper construction which may be impregnated or not as desired. The thickness 50 of the paper or the amount of impregnation of the paper selected for the purpose of giving a required stiffness may of course be varied in order to obtain the desired sound wave reproduction.

The cone 5 may be held in association with the diaphragm 2 in any desired manner in order to obtain the most efficient results. It 55 has been found that the cone may be suitably

and firmly held in association with the diaphragm 2 by forming a flange 6 at the smallest diameter of the cone and pasting or otherwise causing the flange to adhere to the diaphragm 2.

In considering the compound vibrator as a single or unitary element the cone part thereof may be considered as an extension from the diaphragm part.

The most satisfactory sound reproduction 75 results of this compound vibrator have been found when the cone 5 is affixed to a portion of the diaphragm 2 which is free to vibrate. Thus, it will be understood that the cone 5 should not be attached to the parts which bind and support the diaphragm 2, but should be mounted on some part of the diaphragm that is free to vibrate. In the annular type of diaphragm 2, the cone 5 will produce superior results when mounted on some portion of the vibrating diameter of the diaphragm or area. It is desirable in order to obtain some of the most satisfactory reproduction results, to have that area of the diaphragm 2 which is confined within the cone 5, less than three-quarters of the total 80 vibrating area of the diaphragm 2. It has been found that the most satisfactory reproduction is obtained when the cone 5 includes substantially two-thirds of the total area of the vibrating part of the diaphragm.

It is well known that vibrating members such as the diaphragm 2, when mounted as herein illustrated, are exceptionally good reproducers of notes of high frequencies. It is also known that the cone loud speakers are exceptionally good reproducers of notes of low frequencies. The combination of two of such vibrating elements as herein disclosed has been demonstrated to give a much more satisfactory result than any other known single loud speaker instrument.

In Fig. 2 a suitable form of guard is illustrated for protecting the cone 5. This particular form of protection is represented in the form of a wire basket having the feet thereof mounted in the cover 4. It is to be understood that any other suitable type of guard may be employed.

Referring now in particular to Fig. 3, there is indicated a horn 7 which preferably is supported on cover 4 and which acts as a guard for the cone vibrating element 5. This horn 7 also provides a means for amplifying the sound waves set in vibration by both the diaphragm 2 and the cone 5. It will be understood that the vibration of the diaphragm 2 sets the air around it into vibration, and some of this air is pocketed within the confines of the cone 5 while the rest of the vibrating air will be within the confines of the horn 7 and will be amplified thereby. This horn 7 also assists in the amplification of the sound waves set into vibration by the cone 5.

Any suitable means may be employed to satisfactorily set the compound vibrator into operation. The particular form of means which is herein preferred is specifically illustrated in Figs. 4 to 7 inclusive. It is preferred to employ two electro-magnets 8 and 9 in combination with a permanent magnet 10. The electro-magnets are so mounted that their pole pieces 11 and 12 are positioned relatively near to the diaphragm 2. Suitable electrical terminals 14 and 15 are shown for connecting the electro-magnets to a current producing element. It is preferred to have the pole pieces 11 and 12 of L shape so that they may extend down through the windings of the electro-magnets 8 and 9 and be fastened to the extremities of the permanent magnet 10, which in this instance is preferably made up of three laminated plates of semi-circular form.

In most instances it is desirable to adjust the amount of air gap between the diaphragm 2 and the pole pieces 11 and 12 of the magnets for the purposes of locating the most sensitive position for the unit to work in, and it is usually desirable to have the pole pieces as near to the diaphragm as possible without having the diaphragm touch them when vibrating at its greatest amplitude. In many cases it may be desirable to vary the intensity of operation of the loud speakers, and any suitable means may be provided for accomplishing this result. One form of adjustment which has been found satisfactory in the present apparatus consists in a means for moving the pole pieces 11 and 12 to and from the diaphragm 2. This is accomplished by mounting the permanent magnet 10 and the electro-magnets 8 and 9 on a stem 16 which passes through the base-holder 1 and is provided with a suitable nut 17 which may be rotated in one direction or the other to vary the position of the magnets in respect to the diaphragm 2. The construction preferably includes one or more springs 18 which tend to force the pole pieces toward the diaphragm 2. A suitable type of spring is specifically illustrated in Fig. 7 and it will be noted that in Fig. 6 there are two of these springs placed in opposition to one another. If desired, a single spring 18 may be employed and the center thereof may engage the bottom of the base-holder and its free ends engage the semi-circle permanent magnet as may be readily appreciated by reference to Fig. 6. In Figs. 5 and 6, the cover 4 is shown as constructed to receive the base of a suitable horn. This is so illustrated merely to show the adaptability of the operating apparatus, for in Figs. 1 to 3 this cover 4 has been shown cut away to provide for the mounting of a relatively large diameter cone vibrator element and to receive a suitable cone protecting member or a horn 7.

While the manner of mounting the diaphragm has been described above in general terms, it may be stated that it may be substantially firmly mounted or fixedly mounted by inserting fibre gaskets at the edges of the diaphragm and between the lip 3 and the cover 4. The diaphragm may be semi-floatingly mounted by using rubber gaskets in place of the fibre gaskets. If desired, the diaphragm may also be floatingly mounted by using annular gaskets, preferably of a metal, and providing large wave corrugations in these gaskets, thus making them of spring formation.

It will be noted that the invention in its simplest form is an improved loud speaker embodying a novel combination of two vibrating elements which are most efficient respectively for the reproduction of notes of different frequencies. The combination of these two vibrating elements is shown to be accomplished in an improved manner to give a most satisfactory, complete and advantageous tone reproduction. It will be noted that one of the vibrating elements is substantially permanently fixed and that the illustrated means for setting the compound vibrator in operation, acts directly upon only one of said elements, i. e. the permanently fixed vibrating element or part described as a disk diaphragm. It will also be appreciated as desirable in the construction herein disclosed, to have the cone shaped vibrating member firmly affixed to a vibrating portion of the other or disk shaped vibrating member, which is placed in vibration during operation under both high and low frequency impulses. It will further be understood that the two vibrating elements will vibrate in unison or as an integral structure during normal operation, the vibrations of the cone element or part of the compound sound reproducing member being dependent upon the vibrations imparted to the disk element or part thereof, the two elements therefore being in effect, relatively dependent one upon the other in operation. While it has been herein shown that the means for setting the compound vibrator in operation acts directly upon the diaphragm 2 which is permanently mounted, it will be understood that said means may operate upon any part of the compound vibrator constructed with the cone part thereof firmly affixed to some portion of the diaphragm which is free to vibrate.

From the foregoing detailed description of the preferred embodiment of the invention, the operation of my improved sound reproducing device will be readily understood. When a current of electricity under operative conditions is passed through the means for setting the compound vibrator into operation, so as to impart a vibratory movement thereto for the reproduction of

sounds or notes transmitted therethrough, the disk diaphragm will obviously be caused to vibrate to different extents under low as well as high frequency impulses, its fixed position 5 relatively to the pole-pieces of the illustrated energizing means or unit preventing the same from being flexed sufficiently to be drawn into contact with said pole-pieces, yet permitting the same freely to vibrate 10 under the impulses received through said unit. When operated under high frequency impulses imparted thereto through the energizing unit, the disk diaphragm will vibrate under the normal conditions of an ordinary 15 disk diaphragm, with the cone which is secured thereto vibrating as an integral and unimpeded or unresisting part thereof but acting as a horn for the vibrating portion of said disk diaphragm, thereby amplifying 20 the sounds emitted therethrough. When operated under low frequency impulses imparted thereto through the energizing unit, the disk diaphragm which is of a higher 25 periodicity than the cone diaphragm will be caused to vibrate sufficiently to impart vibrations therethrough to said cone of lower periodicity so that the latter will be more violently vibrated and reproduce the sounds transmitted at the lower frequencies, the 30 horn surrounding said cone serving to amplify the sound or sounds reproduced thereby. It will be noted that the cone diaphragm is entirely supported on the disk diaphragm and has no connection with the horn or 35 other element at its outer end and it will therefore be apparent that the cone and disk diaphragms comprising the compound vibrating element are dependent one upon the other in operation, since vibrations can be 40 imparted to the cone diaphragm only through the disk diaphragm while said cone offers no resistance to the natural vibrations of the disk diaphragm which is effectively responsive to the higher frequency impulses 45 to which the cone diaphragm will not respond. Thus my improved sound reproducing device with compound vibrator is adapted to effectually and clearly reproduce sounds and notes within a much wider range 50 of frequency impulses than that to which the ordinary disk and cone diaphragms will individually respond, the one element of the compound vibrator being adapted to effectual reproduction of sound where the other 55 becomes ineffectual, that is, the one of said elements being adapted to be effectually vibrated in the reproduction of sound where the other would cease to vibrate in response 60 to frequency impulses, due to the differences in their periodicity. The advantages and superiority of my improved sounding device over sound reproducing devices heretofore known and used will therefore be readily appreciated.

65 It will be understood that while there has

been herein described in detail a particular embodiment of the invention for purposes of full disclosures, and some detailed features which are specifically claimed for a special advantage, many changes and modifications may be made in the particular construction and arrangement of parts without departing from the broad scope of the invention which is outlined in the appended claims. 70 75

I claim:

1. In a sound reproducing mechanism, the combination of a compound vibrator having that portion thereof which reproduces notes of high frequencies fixedly mounted and 80 having the portion which reproduces notes of low frequencies in association with said first portion to vibrate in unison therewith, and means associated with only the permanently mounted portion for operating said 85 compound vibrator.

2. In a sound reproducing mechanism, the combination of a compound vibrator having a part thereof fixedly mounted and adapted to reproduce notes of high frequencies and 90 having a second part thereof firmly attached to the vibrating part of the first part, said second part being adapted to reproduce notes of low frequencies, and means for operating 95 the compound vibrator.

3. In a sound reproducing mechanism, the combination of a compound vibrator having fixedly mounted the part thereof which reproduces notes of high frequencies and having a second part attached to the vibrating portion of the first part, said second part being adapted to reproduce notes of 100 low frequencies, and means for operating said compound vibrator.

4. In a sound reproducing instrument, the combination of a part adapted to reproduce notes of high frequencies, said part being mounted in a fixed support and being constructed of metal, a second vibrating part attached to a vibrating portion of said first part and being constructed of material other than that of said first part, and means for 105 vibrating said parts in unison.

5. In a sound reproducing instrument, the combination of a vibrating part mounted on a fixed support, a second vibrating part mounted on a vibrating portion of said first part, said second part being constructed of a material of lighter weight than the first part and being of greater size than the first 110 part, and means for setting said parts into vibration to produce sound waves.

6. In a sound reproducing instrument, the combination of a compound vibrator having a high frequency vibrating part thereof mounted in a fixed support and having a low frequency vibrating part thereof affixed to a vibrating portion of said first named part and being entirely supported by said first part, and means for operating said 125 first part, and means for operating said 130

- compound vibrator for reproducing sound waves.
7. In a sound reproducing mechanism, the combination of a vibrating part for the reproduction of notes of high frequencies, a second vibrating part for the reproduction of notes of low frequencies, said parts being joined together so that only a portion of the vibrations of one of the parts will be transmitted to the other vibrating part, and means acting on one of the parts to vibrate both parts.
8. In a sound reproducing instrument, the combination of a diaphragm adapted to reproduce notes of high frequencies, a cone shaped vibrating member mounted on a vibrating portion of said diaphragm, and means for setting said diaphragm and said cone member into vibration.
9. In a sound reproducing instrument, the combination of a diaphragm vibrating member, a cone vibrating member, said members being connected together and adapted to reproduce sound waves, and means mechanically unconnected with either of said members for vibrating the same in unison.
10. In a sound reproducing instrument, a vibrating sound reproducing element consisting of a relatively flat part mounted in a fixed support and an extension therefrom in the form of a cone brought into sound reproducing vibration by the vibrations of said relatively flat part.
11. In a sound reproducing instrument, the combination of a diaphragm adapted to be vibrated, a second and cone-shaped diaphragm having its small end affixed upon a limited area of the first diaphragm so that a limited portion of the air set into vibration by the first diaphragm will be confined within the cone diaphragm, and means for vibrating said diaphragms in unison.
12. In a sound reproducing instrument, the combination of a metal diaphragm permanently mounted, a cone shaped vibrating sound reproducing member affixed to said diaphragm, the area of said diaphragm confined within the cone member at the point of attachment being less than three-quarters of the total area of the vibrating part of said diaphragm.
13. In a sound reproducing instrument, the combination of an annular diaphragm permanently mounted at its edge, and a cone-shaped vibrating member of greater size than said diaphragm and being firmly attached to said diaphragm, the diameter of said cone member at the point of attachment to said diaphragm being substantially equal to two-thirds the diameter of the vibrating portion of said diaphragm.
14. In a sound reproducing instrument, the combination of a metal diaphragm having its edge clamped to permanently mount the same in said instrument, a cone-shaped paper vibrating member pasted to a vibrating portion of said diaphragm, the part of said cone member in engagement with said diaphragm adapted to enclose about two-thirds of the vibrating area of said diaphragm.
15. In a sound reproducing instrument, the combination of a disk diaphragm adapted to be vibrated, a cone vibrating member affixed to a vibrating portion of said disk diaphragm, a horn adapted to surround and protect said cone and also acting to amplify some of the vibrations from said disk diaphragm, and means for vibrating said diaphragm and said cone in unison.
16. In a sound reproducing instrument, the combination of a disk diaphragm adapted to be vibrated, a cone vibrating member supported on a vibrating portion of said disk diaphragm, a horn adapted to surround and protect said cone and also acting to amplify some of the vibrations from said disk diaphragm, means for vibrating said disk diaphragm and said cone in unison, and means for adjusting the vibrating means to vary the amplitude of vibration of said diaphragm and said cone member.
17. In a sound reproducing instrument, the combination of a disk diaphragm adapted to be vibrated, a second and cone-shaped diaphragm affixed upon a limited area of the disk diaphragm so that only a portion of the air set into vibration by said disk diaphragm will be confined within the cone diaphragm, means for vibrating said diaphragms in unison, and a horn surrounding said cone-shaped diaphragm and adapted to amplify some of the vibrations of said disk diaphragm.
18. In a loud speaker, the combination of a base-holder, an annular metal diaphragm having its edge permanently held in said base-holder, a cone-shaped member of paper material having a turned-in flange at its smallest diameter and adapted to have said flange pasted to said diaphragm, the smallest diameter of said cone being substantially two-thirds of the vibrating diameter of said diaphragm, a horn mounted on said base-holder and extending therefrom to protect said cone and acting also to amplify some of the vibrations of said diaphragm, a magnet for vibrating said diaphragm and said cone member, and adjusting means responsive to spring pressures for moving said magnet relatively to said diaphragm to thereby vary the amplitude of vibration of said diaphragm and said cone.
19. In a sound reproducing mechanism, the combination of a compound vibrator having a part thereof adapted to reproduce notes of high frequencies and having a second part thereof supported on a vibrating portion of the first named vibrating part,

said second named part being adapted to reproduce notes of low frequencies, and means for operating the compound vibrator. 20

20. In a sound reproducer, a compound vibrator comprising a diaphragm having a high natural period and a diaphragm having a low natural period, said last mentioned diaphragm being supported on the first mentioned diaphragm and so related thereto 10 as to provide an amplifying means therefor, together with means for setting the compound vibrator into operation.

21. In a sound reproducer, a diaphragm having a high natural period, a diaphragm 15 having a low natural period, said last mentioned diaphragm being supported on the first mentioned diaphragm and vibrated therewith, and means acting directly on one

of said diaphragms for setting the same in operation. 25

22. In a sound reproducer, a compound vibrator element comprising a disk diaphragm having a high natural period and a cone-shaped diaphragm having a low natural period supported thereon and providing an amplifying means for the former, together with means for setting the compound vibrator in operation. 25

23. In a sound reproducer, a diaphragm having a high natural period, a diaphragm having a low natural period and entirely supported on said first mentioned diaphragm, and means for operatively vibrating said diaphragms. 30

In testimony whereof I affix my signature.
ARTHUR WILLIAM HARRIS.
